CLAIM

The ornamental design for a racket handle attachment, as shown and described.

DESCRIPTION

FIG. 1 is a perspective view of a racket handle attachment illustrating the claimed design;

FIG. 2 is a front view of the racket handle attachment shown in FIG. 1;

FIG. 3 is a back view of the racket handle attachment shown in FIG. 1;

FIG. 4 is a left side view of the racket handle attachment shown in FIG. 1;

FIG. 5 is a right side view of the racket handle attachment shown in FIG. 1;

FIG. 6 is a bottom view of the racket handle attachment shown in FIG. 1;

FIG. 7 is a top view of the racket handle attachment shown in FIG. 1;

FIG. 8 is a front view of the racket handle attachment in exemplary use on an unclaimed handle of a racket; and,

FIG. 9 is a side view of the racket handle attachment in exemplary use on an unclaimed handle of a racket.

The broken lines in the drawings are for illustrative purposes

only and form no part of the claimed design.

1 Claim, 6 Drawing Sheets
